HINGE

Marie Witschi, Batterkinden, Switzerland, assignor to Sepa Scharnier A.-G., Olten, Switzerland, a corporation of Switzerland

Application November 18, 1938, Serial No. 241,154
In Switzerland November 22, 1937

2 Claims. (Cl. 16—164)

The present invention relates to a hinge for doors, windows, furniture and so forth.

The new hinge consists of parts which preferably agree in pairs in shape and dimensions and which are all connected together hingedly. None of the parts is subjected to excessive strain which would lead to a change of shape of the parts or to a rapid wear thereof. All the parts of the hinge are invisible when the door or the like is closed. They fit into recesses in the door frame, door panels and so forth. The parts of the hinge may consist of extrusion castings or be formed of sheet metal by stamping and pressing.

15 An example of construction in accordance with the invention is shown in the accompanying drawing, wherein.

Fig. 1 is a plan of the open hinge.

Fig. 2 is a corresponding plan of the closed hinge.

Fig. 3 is a side elevation.

Figs. 4 to 9 each show a partial elevation of the six separate parts forming the hinge, without the hinge pin, and

25 Figs. 10 to 19 are sections respectively on the lines X—X to XIX—XIX of Figs. 4 to 9.

The first hinge plate 1 is provided with screw holes 2 for the purpose of enabling it to be secured to one of the parts to be connected. The hinge joint located adjacent the said screw holes, is provided with three coaxial hinge eyes 3, projecting above the hinge plate, which are separated from one another by intervening recesses 4. The hinge joint remote from the screw holes 35 and extending parallel to the hinge eyes 3 is preferably in alignment with the edge of the hinge plate. It is also provided with three coaxial hinge eyes 5, projecting above the hinge plate, which are separated by recesses 6. The arrangement of the last mentioned hinge joint is preferably such that the hinge eyes 5 are opposite the recesses 4 and the hinge eyes 3 are opposite the recesses 6.

40 The first connecting band 7 is provided on both sides with symmetrically arranged hinge eyes 8 and 9, which are so arranged that they fit into the recesses 4 of the hinge plate 1. By means of abutments 11, provided on the connecting band 7, the hinge is prevented from being rocked beyond a predetermined open position.

45 The first main hinge band 12 is of angular shape as shown in Figs. 14 and 15 and is provided with three hinge lugs 13 at the ends of which are provided the downwardly directed coaxial eyes 15, which fit into the recesses 6 of the hinge plate 1 and for this purpose are spaced apart

by the recesses 16. In the base of the lugs, which is located approximately at the centre of the width of the main hinge band 12, are provided the main hinge eyes 17. Opposite the recesses 16 there are provided at the other end of the main hinge band 12, hinge eyes 18 which are separated from one another by recesses 19.

The second main hinge band 12' is provided in the same manner as the first main hinge band 12, with hinge lugs 13', hinge eyes 18', hinge eyes 15', recesses 16' and 19' and main hinge eyes 17', of which the dimensions are such as to enable the hinge to be assembled in the manner to be described hereinafter.

15 The second control band 7', shown in Figs. 12, 13 and 8, is provided in a similar manner to the first control band 7 with hinge eyes 8' and 9', and abutments 11'.

20 The second hinge plate 1' is of the same construction as the first hinge plate 1 and consequently is provided with screw holes 2', hinge eyes 3' and 5' and with recesses 4' and 6'.

The assembly of the parts shown in Figs. 4 to 19 for forming the hinge capable of being used is effected in the following manner. The control band 7 or 7' is fitted into the recesses 4 or 4' while the hinge eyes 3 or 3' come to lie on the hinge eyes 8 or 8', so that a hinge pin can be passed through the hinge eyes located along an axis and thus form a hinged connection between the hinge plate 1 or 1' and the control band 7 or 7'. The main hinge bands 12, 12' are so arranged crosswise that the hinge eyes 15 and 18' or 15' and 18 are located on the same side of the hinge and the main hinge eyes 17 and 17' are located along 25 one and the same axis so that they can be connected together hingedly by a hinge pin passed therethrough. The hinge eyes 15 or 15' are brought into a position so as to lie coaxially with the hinge eyes 5 or 5' by reason of the recesses 6 or 6' so that the hinge plate 1 or 1' is hingedly connected to the main hinge band 12 or 12'. The control band 7 or 7' is connected by its hinge bands 9 or 9' to the hinge bands 18 or 18' by means of a hinge pin, whereby during the closing movements the main hinge joint carries out a positive parallel movement to itself into the interior of the hinge by reason of the double hinge action.

30 For applying the present hinge to articles of furniture, doors, windows and the like, the hinge plates 1 and 1' are counter-sunk as shown in Figs. 1 and 2, so that when the hinge is closed none of the fittings are visible.

40 In comparison with known hinges which are 35

45

50

55

not visible in the closed position, the present hinge possesses the great advantage that the parts thereof co-operate with one another exclusively hingedly, whereby neither wear, which produces increased relative movement of the separate parts, or increased resilient deformations are produced, which deformations always involve the liability of fractures as a result of fatigue. The hinge according to the present invention is preferably produced by the extrusion casting process or from sheet metal by the stamping process.

I claim:

1. A hinge comprising a pair of base plates, two sets of apertured lugs on each of said base plates, one set of lugs being located adjacent one longitudinal edge of the base plates and the second set of lugs being arranged parallel to the first set but relatively displaced thereto, said base plates having recesses between said apertured lugs, a pair of double-armed levers arranged crosswise to one another, the arms of said levers, being at an angle to one another, said levers having lugs and recesses located along the centre line thereof, the recesses of one lever being adapted to receive the lugs of the other lever, said lugs being apertured, a hinge pin extending through the lugs of

said levers, one arm of each of said levers having spaced lugs arranged at right angles to said arm, the right-angled lugs of one lever being hingedly connected to the lugs at the edge of one plate, while the right-angled lugs of the other lever are hingedly connected to the lugs at the edge of the second plate, spaced apertured lugs at the ends of the other arms of said levers, and a pair of links, one link being engaged with the lugs at the end of one lever arm and the inner set 10 of lugs on the corresponding plate, while the second link is hingedly connected to the lugs of the second lever and to the second set of lugs on the corresponding plate, the whole arrangement for the purpose that the plates with the 15 lugs and levers form a closed protecting surface against dirt in all positions of the hinge.

2. A hinge according to claim 1, wherein the separate parts are so dimensioned that in the open position of the hinge the links rest against the levers which form a stop for said links, by virtue of the whole arrangement the plates will always reach exactly the same open position and no excessive strain will be exerted on the plates.

MARIE WITSCHI.
